(57) **CLAIM**

The ornamental design for the table, as shown and described.

DESCRIPTION

FIG. 1 is an isometric view of the table of the present design; FIG. 2 is a right side elevation view thereof, the left side elevation view being identical thereto; FIG. 3 is a front elevation view thereof, the rear elevation view being identical thereto; and, FIG. 4 is a top plan view thereof. The broken lines in the figures are for illustrative purposes only and form no part of the claimed invention.
